UNITED STATES PATENT OFFICE.

EDWIN H. ATWOOD, WALTER E. WANNER, CLARENCE A. KIEHLE, AND EDWARD H. WRIGHT, OF OLEAN, NEW YORK, ASSIGNEES TO VACUUM OIL COMPANY, OF NEW YORK, N. Y., A CORPORATION OF NEW YORK.

CLEANING MACHINE FOR CONTAINERS.

Application filed May 26, 1926. Serial No. 111,848.

The present invention relates to cleaning machines for barrels or other circular containers and an object thereof is to provide a construction in which the barrel or container is carried through a liquid tank or bath partially in a submerged condition, while at the same time being rotated to effect contact between the bath and the entire surface of the barrel or container. Another object of the invention is to provide a construction in which the barrel is constructed to roll on a trackway at its uppermost portion while travelling through a bath so that the trackway serves to hold the barrel or container against rising in the bath and, at the same time, causes the rotation of the barrel or container.

To these and other ends, the invention consists of certain parts and combinations of parts, all of which will be hereinafter described, the novel features being pointed out in the appended claims.

In the drawings:

Fig. 1 is a plan view, with parts broken away, of an apparatus constructed in accordance with this invention;

Fig. 2 is an enlarged plan view of the intake end of the machine;

Fig. 3 is a section of the intake end of the machine as illustrated in Fig. 2;

Fig. 4 is a plan view of the discharge end of the machine;

Fig. 5 is a plan view of an intermediate portion of the machine;

Fig. 6 is a side view of the same portion;

Fig. 7 is a side view of the discharge portion of the machine;

Fig. 8 is a section on the line 8—8, Fig. 1; and

Fig. 9 is a section on the line 9—9, Fig. 1.

Referring more particularly to the embodiment of the invention, 1 indicates an elongated concrete base which is formed, in this instance, with a longitudinally extending channel 2 opening at its top. Supported in the side walls of this chamber are cross beams 3, in this instance of channel formation, the ends of the beams being anchored in the base 1. On these cross beams is supported an immersing tank 4 formed, in this instance, of sheet metal and having its opposite ends 6 and 7 inclined and supported in spaced relation to the ends 8 and 9 of the concrete base so that an entrance and an

outlet are provided. This arrangement provides a chamber beneath the tank 4 which opens vertically beyond the opposite ends of the tank.

Vertical supports 11 resting on the concrete base 1 may rise vertically from the latter on the outer sides of the tank 4 and are connected by cross pieces 12. These cross pieces 12 form supports for a trackway arranged above the tank 4. This trackway, in this instance, comprises two longitudinally extending tracks 13 formed of channel beams secured to the under side of the cross pieces 12 and connected by tie rods 14 which hold them in parallel relation. The ends of these tracks 13 are deflected upwardly at 15 and 16 above the inclined portions 6 and 7, respectively, so that barrels or containers travelling down the inclined portion 6 and up the inclined portion 7 are guided onto and from the tracks 13.

Within the tank 4 is contained the bath to which the barrels or containers are subjected while travelling on the trackway 13 through the tank 4. This bath may contain any suitable chemical which will attack grease, paint or dirt on the exterior of the barrel, the barrel being made air tight so that the contents of the bath cannot enter the interior of the barrel or container and, at the same time, the air within the barrel gives the latter a tendency to float on the top of the liquid. However, the tracks 13 are so positioned that they hold the barrel over half submerged in the bath, so that as the barrel travels along the trackway it rotates and the entire surface of the barrel is subjected to the action of the bath.

A suitable means for moving the barrel or containers through the bath may be employed. In this instance, an endless conveyor has one lap operating through the bath beneath the trackway and the other lap operating below the tank containing the bath and within the channeled base 1. This conveyor, in this instance, embodies two sprocket chains 17 and 18 connected by tie rods 19 so that they move together, these tie rods each preferably having provided thereon two rollers 20. These rods preferably also project beyond the sprocket chains and on their projecting ends are provided with rollers 21 which operate in grooved ways formed on opposite sides of the tank 4. Each of these

grooved ways embodies an upper angle iron member 22 and a lower angle iron member 23, the upper angle iron member being deflected upwardly at 24 at both ends in order 5 to facilitate the entrance of the rollers 21 between the members 22 and 23. The lower member 23 is extended at both ends beyond the curved ends 24 of the member 22 and upwardly over the inclined end portions 6 and 10 7 of the tank 4, so that the rollers 21 travel on said extensions as the conveyor moves into and out of the tank.

The forward end of the conveyor may be supported by two sprockets 26 on a shaft 27 15 supported on the base 1, the shaft 27 being mounted in bearings 28 which through take-up screws 29 will shift for the purpose of securing the slack in the upper end of the conveyor. The discharge end of the conveyor passes about sprockets 30 on a shaft 31 20 which is supported on the base 1 and is driven in any suitable manner as by a large gear 32 on said shaft meshing with a pinion 33 on a counter-shaft 34 which has a gear 35 meshing with a pinion 36 on a worm wheel shaft 37 which meshes with the worm, not shown, on the motor shaft 38. This train of gearing between the motor shaft 38 and the shaft 31 acts as a reducing gearing 25 30 between the motor 39 and the shaft, so that the endless conveyor travels slowly as compared with the speed of rotation of the motor.

The lower lap of the conveyor as before 35 pointed out, passes between the ends of the tank and the base member and through the channel or chamber formed beneath the tank 4. In this instance, the rollers 20 travel on the channel trackways 40 arranged on the 40 bottom of the channeled base 1 and in order that the lower lap of the conveyor may not accidentally rise and engage the cross-beams 3, longitudinally extending plates 41 are arranged on the underside of the cross beams 45 3 between the channel trackways 40.

The barrels or containers pass to the machine preferably on tracks 42 and these tracks have adjustable extensions 43 which project forwardly toward the conveyor so 50 that the barrels come to rest between the ends of these extensions 43 and the receiving ends of two tracks 44. These tracks 44 are supported on the shaft 27 and have their receiving ends curved downwardly at 45, their 55 other ends being extended over the inclined receiving end 6 of the tank so that when the rollers 20 pass upwardly at the receiving end of the conveyor they engage with a barrel resting between the ends of the track 43 and the receiving track 44 and move said barrel forwardly on said receiving tracks until it reaches the inclined bottom 6 of the tank when the barrel or container moves down such inclined bottom between two sets 60 65 of rollers 20 on two different cross bars 19.

As the barrel or container passes down the bottom 6 of the receiving end of the tank, it eventually passes under the curved ends 5 of the trackway formed by the channel members 13. When it reaches the horizontal 70 portion of this trackway, the barrel or container is within the main body portion of the tank which is filled to such a point that the liquid rises above the central axis of the barrel or container. Thereafter, the barrel or container rolls along the trackway formed by the channel irons 13, being held against said trackway by the buoyancy of the barrel or container and being moved along the 75 trackway by the endless conveyor. As a consequence, the barrel or container is rotated and all portions thereof are subjected to the action of the bath. The tank is of such length that this bath when containing one or more chemicals to attack the paint or grease 80 on the surface of the container will have sufficient time to perform such function. After the barrel or container has passed through the main body portion of the tank or bath, it reaches the discharge end of the latter 85 and is rolled up the inclined portion 7 and onto the rollers 46 arranged on the shaft 31 at the discharge end of the machine, these rollers engaging the barrel to direct it onto a suitable trackway not shown, which may 90 lead to a scrubbing or other cleaning mechanism of any suitable type. 95

From the foregoing it will be seen that there has been provided a barrel cleaning machine in which a barrel or container is 100 moved through a liquid bath and held partially submerged in said bath by a trackway engaging the uppermost portion of the barrel or container and acting also to rotate such barrel or container in its movement 105 through the bath so that all portions of the barrel or container are subjected to the action of the bath. In moving through the bath, the barrel or container is operated upon by an endless conveyor which, in this instance, 110 embodies two outer endless members or sprocket chains connected by cross pieces between which the barrel or container lies. These cross pieces are provided with rollers which make it impossible for the cross pieces 115 to interfere with the rotation of the barrel or container in its travel through the liquid bath.

What we claim as our invention and desire to secure by Letters Patent is:

1. A container cleaning machine embodying an elongated tank providing a bath, a trackway extending longitudinally of the tank in spaced relation to the bottom for engaging the uppermost part of a container travelling through said tank to hold it at least partially submerged in the bath, and means for moving said container through the tank with its uppermost portion in engagement with the trackway to cause the con- 120 125 130

- tainer to be rotated while moving through the bath, said means extending beyond opposite ends of the trackway to move the container under and from under the trackway.
5. In a container cleaning machine, the combination with an elongated tank with end portions provided with inclined bottoms, of an endless conveyor for moving a container through the tank having a lap operating over said inclined bottoms to move the containers down one end portion and up the other of 45 said inclined bottoms, and a trackway for cooperating with the upper portions of a container moved by said endless conveyor, said trackway having its ends deflected upwardly over said inclined bottoms. 50
6. In a container cleaning machine, the combination with a base member provided with a longitudinally extending channel, of cross pieces bridging the channel of the base member, a tank supported on said cross 55 pieces over said channel, and a conveyor having one lap operating above the tank and the other lap operating below the tank in said channel.
7. In a container cleaning machine, the 60 combination with a base member provided with a longitudinally extending channel, of cross pieces bridging the channel of the base member, a tank supported on said cross pieces over said channel, a conveyor having 65 one lap operating above the tank and the other lap operating below the tank in said channel, and trackways arranged on the bottom of the channelled base and supporting the lower lap of the conveyor.
4. In a container cleaning machine, an 30 elongated tank for holding the liquid bath, an endless conveyor having a lap operating through the tank to move containers through the tank, and a trackway arranged above said lap to cooperate with uppermost portions of 35 the containers moved by such lap through the tank, the opposite ends of the track being curved upwardly and being situated between the ends of the lap.
